UNITED STATES PATENT OFFICE.

DOUGLAS STUART SPENS STEUART, OF LONDON, ENGLAND.

TELEPHONE ACCESSORY.

Application filed October 21, 1927, Serial No. 227,815, and in Great Britain January 26, 1926.

This invention relates to an improved telephone accessory and more particularly has for its object the provision of an accessory to enable the usual fixed telephone transmitter to be used in a more convenient manner than has hitherto been possible, although it should be understood that certain features of the invention may be utilized for other allied purposes.

It is well established practice in the telephone art that the transmitter in central battery working should be connected to a fixed and more or less rigid support, and for this reason in certain countries the use of such a solid back transmitter as distinct from a handset is insisted upon so as to retain all the advantages which a fixed transmitter has over the capsule transmitter in the handset. A handset is liable to be turned to all angles and held in a variety of positions, some of which positions render speaking very unsatisfactory; in fact in a number of handsets the circuit from the exchange may be actually broken, causing a disconnect signal to be given, or in the case of an automatic telephone system causing the whole of the switches to be released. On the other hand the handset has certain advantages from the point of view of the telephone user, as it will be appreciated that the ordinary type of table telephone or wall telephone necessitates the subscriber placing his mouth close up to the mouthpiece. There are several disadvantages to this, one of which is, that it is very difficult to read a message over the telephone and it is also difficult to write down a telephone message received. In the case of the pillar-type telephone it is often necessary to lift or move the whole of the telephone so as to bring it right in front of the subscriber, and it then becomes difficult at the same time to write on or read from papers on the desk.

The principal object of this invention is, therefore, the diminution or abolition of strain to the subscriber, and the increase of the facilities which the telephone can render to the subscriber, and the principal feature of this invention consists of providing an exceedingly light flexible tube extending from the transmitter of either a wall or pillar-type telephone to a mouthpiece which may be supported at a distance from the telephone and in a position most convenient to the subscriber.

It is important, in order that the sub-

scriber's hand may be free, that such a mouthpiece should be supported independently and accordingly a further feature of the invention consists of supporting means adjustable with the mouthpiece and extending from the vicinity of the transmitter so that the mouthpiece may be automatically supported in any desired position to which it may be put. No part of the telephone therefore need rest on the desk immediately in front of a subscriber and accordingly this part of the desk is clear for either reading or writing. It is found that by carefully constructing such a flexible tube the sound received by the transmitter is as great, or greater, than is received when the mouth is held up close to the usual transmitter mouthpiece in accordance with the instructions issued by the telephone operating companies or administrations. The further feature of the invention therefore concerns the provision of special supporting means whereby the flexible tube can be placed in any desired position and can stay in the position in which it is put. It should be mentioned that the length of the flexible tube would usually correspond with the length of the receiver cord so that the subscriber's mouth could be at a distance from the transmitter equal to the distance to which he could extend the receiver to his ear.

In certain telephone administrations the regulations insist that no attachments should be made to the telephone of any kind whatever, and in order to enable the present invention to be used without infringing any of such regulations a further feature of the invention consists in providing a stand on which the pillar-type telephone will rest and which is firmly held owing to the weight of the telephone, this stand having a projection to which a ferrule suitably shaped is secured, preferably with freedom to move so as to adjust itself into a position to fit in the ordinary telephone mouthpiece when the telephone is placed on the stand. This ferrule is secured to one end of the flexible tube, the other end of the flexible tube carrying the mouthpiece and being supported as previously described.

These and other features of the invention will be better understood by referring to the accompanying drawings, in which Fig. 1 represents one example of carrying the invention into effect, in which a ball and

socket joint is used as a means whereby the mouthpiece at the end of the flexible tube may be supported in any desired position; Figs. 2 and 3 represent an alternative form which avoids the use of a joint and yet enables the mouthpiece to be supported in a variety of positions, and Fig. 4 shows a third form and illustrates in full how the invention may be applied to a pillar-type telephone without any attachment, clips, or the line.

Referring to Fig. 1, the pillar-type telephone 10 is shown carrying at its upper end in the usual manner the transmitter with its casing 11. From this transmitter the usual mouthpiece has been removed and in place thereof a ferrule 12 is screwed in. This ferrule has attached to it a flexible tube 13 which it is important should be light and durable, and at the same time should permit a free passage of the sound waves without loss of efficiency. At the end of the flexible tube 13 is fitted a mouthpiece 14, which mouthpiece is considerably larger than the usual mouthpiece and is shaped somewhat as shown. This enlarged mouthpiece has the advantage that the user is not nearly so restricted owing to its size even when he wishes to speak right up to the mouthpiece, but it should be understood that he can speak with considerable efficiency a few inches away from the mouthpiece, while being still perfectly audible to a listener at the other end of the telephone. Embracing the mouthpiece and secured thereto is a ring 15 having a projection 16 adapted to engage a socket 17 secured on the end of a rod 18. The engagement between 16 and 17 is such that while it makes a stiff friction tight joint which secures the ring 15 to the rod 18, it permits freedom of rotation so that the projection 16 is pivoted in socket 17. The rod 18 slides in a tube 19 in telescopic manner, while the tube 19 is screwed into a ball 20. It will be understood that a number of telescopic tubes could be provided intermediate the rod 18 and the tube 19 so as to give any desired length of extension of the distance between the ball 20 and the pivot 17. The telescopic attachment, including the rods 18 and 19 which would be of the usual well known design for this type of fitting and would be made of very light material such as aluminum, would be preferably slightly friction tight. The ball 20 rests in a cup 21 provided with friction material 22 at its outer edge against which the ball may be forced by a screw 23 so as to regulate the degree of friction. The cup 22, it should be understood is, of course, slightly greater than a hemisphere so that it actually embraces the ball and the edge 22 holds the ball when it is pressed outward by the screw 23. This cup 21 is supported on an arm 24 fixed to a sleeve or collar 25 that fits over the ferrule

12. A ring 26 fits, in turn, over collar 25 and carries a forked member 27 in the fork of which the mouthpiece 14 may be placed when not in use. Generally speaking, this member may be dispensed with as the telescopic fixture, including the rod 18 and the tube 19, will hold the mouthpiece in a position as shown by simply placing the mouthpiece in such position when it is finished with and not required. When it is required, the subscriber removes the mouthpiece out of the fork or cradle 27 and places it as shown in dotted lines, assuming that the position shown is convenient. The friction tight ball joint would be regulated so that the mouthpiece would be held in any position in which it may be put. It will be appreciated that for this purpose not only the telescopic members, but also the tube and mouthpiece, must be exceedingly light in weight. It will be noted that the telescopic joint enables the radial distance of the mouthpiece from the ball 20 to be varied as desired, while the ball joint permits the mouthpiece to be moved in any circumferential direction.

Referring to the alternative shown in Figs. 2 and 3, all joints are avoided by this construction. The ferrule 12 and tube 13 are similar to those shown in Fig. 1. The forked member 27 is also similar. The collar 25 carries a special frame 28 shown in perspective view in Fig. 3. This frame comprises two semi-cylindrical shells 29, 30, of different diameters, with the smaller extending upwards from the top of the larger one, so as to form two shoulders 31 and 32 at different vertical heights; to the upper shoulder a stirrup 33 is attached as is also the collar 25. A rod 18 is pivotally connected to the ring 15 as before. The rod 18 can be a straight rod or if desired can be telescopic. In the drawing, it is shown as a straight rod and the operation is as follows: Normally the mouthpiece 14 would rest in the cradle 27, but when it is desired to speak, the mouthpiece would be lifted from the cradle, and the rod 18, which hangs down in the opening between the stirrup 33 and the semicylindrical shells 29 and 30, is lifted and is placed in either of the two positions shown in dotted lines, according to the height at which it is desired to normally maintain the mouthpiece. It is clear that the number of shoulders could be varied so that instead of having two steps or two planes in which the mouthpiece can move, there could be three, four, or any other number, by simply providing further shoulders such as 31 and 32. The stirrup 33, as will be seen, acts as a pivot and this arrangement avoids the necessity of any complicated joint.

A third construction is shown in Fig. 4. Referring to this figure it will be seen that the pillar-type telephone 10 is placed on a

stand 36 which has a sloping upper surface so as to tilt the transmitter for a purpose to be described later. Rising from the stand 36 is a socket 37, and an extension piece 38 is also provided on the stand. The extension piece 38 is for the purpose of increasing the stability of the arrangement to reduce the danger of it being capsized when the flexible tube carrying the mouthpiece is extended to its furthest position. It is assumed that the pillar-type telephone 10 is exactly as supplied by a telephone operating company and that it is not desired to attach or clip any external apparatus to such instrument. Consequently the usual mouthpiece 39 is left screwed into the transmitter casing 11. In the socket 37 is fitted a shaped rod 40 which is of such a size as to have a good fit therein while still being capable of movement for transport purposes when desired. The shaped rod 40 extends upwards to near the transmitter and then bends out at right-angles, as shown, and carries at its end an elbow piece 46 having a vertical socket 41. In this socket a ferrule 42 connected to the end of the flexible tube 13 is secured by means of the milled headed screw 43 which engages a circular rod 44 secured to the ferrule 42. As the elbow piece is also pivoted on the rod 40 and capable of being secured where desired by the milled screw 53 it is possible by means of these arrangements to adjust the ferrule to such a position that its shaped end 45 can enter the mouthpiece 39 and fit snugly therein when the telephone 10 is placed on the base or stand 36. It will therefore be appreciated that the object of the slope is to cause the mouthpiece 39 to press against the shaped end 45 and therefore insure a tight fit, which is important, as not only the transmitter is protected from extraneous noises but also the speech is received by the transmitter in a more efficient manner. Intermediate the socket 41 and the elbow of the elbow piece 46, a collar 47 is pivoted, which collar carries a forked member 48. The collar is free to turn about the vertical portion of the elbow piece 46. At the outer end of each arm of the fork 48 is pivoted a series of articulated arms 49, 50. These articulated arms are connected at their joints in such a manner that they can move relatively to each other but with considerable friction; for instance, this could be effected by screws and nuts pressing on a spring washer, as is well known. The two series of articulated arms 49, 50 extend on each side of the flexible tube 13, which is provided with a ferrule 51 at the mouthpiece end to which the mouthpiece 14 is secured. It should be mentioned that the joint of the arms 50 to the ferrule 51 is similar to the joints between the arms 48 and 49, and 49 and 50, and permits a rotary

movement of the mouthpiece 14 relative thereto. The articulated arms would be made of very light material such as duralumin. Between the opposite joints of each series of articulated arms are straps 52 which engage with the flexible tube 13 and so move it to any desired position as the mouthpiece 14 is moved; in dotted lines the mouthpiece is shown moved to its extended position, whereas the full lines show the position which the mouthpiece may occupy when not in use. It will be noted that a considerable advantage of this construction is that the desk space is left quite free under the mouthpiece and therefore the subscriber when using the telephone has substantially an unobstructed vision of his desk and papers lying thereon. He can have the mouthpiece in the position most convenient to him and can be perfectly free in that he has not to hold the mouthpiece at all, the mouthpiece staying in any position to which it may be put.

I claim:—

1. In combination a telephone transmitter, a mouthpiece for said transmitter, a flexible tube extending from said transmitter to said mouthpiece, and a universally movable support for said mouthpiece. 90

2. In combination a telephone transmitter, a mouthpiece for said transmitter, a flexible tube extending from said transmitter, and a stiff universally movable support for said mouthpiece extending from the vicinity of the transmitter to said mouthpiece. 95 100

3. In combination a pillar-type telephone instrument, a transmitter mounted on said instrument, a stand on which said pillar-type telephone rests, a mouthpiece on said transmitter, a tube, a ferrule shaped so as to fit into said mouthpiece and connected at one end of said tube, a supporting member fixed to said stand and arranged to hold said ferrule in position in said mouthpiece, and a second mouthpiece connected at the other end of said tube. 105 110

4. In combination a pillar-type telephone instrument, a transmitter mounted on said instrument, a stand on which said pillar-type telephone rests, a mouthpiece on said transmitter, a flexible tube, a ferrule shaped so as to fit into said mouthpiece and connected at one end of said flexible tube, a supporting member fixed to said stand and arranged to hold said ferrule in position in said mouthpiece, a second mouthpiece connected at the other end of said tube, and a second supporting member connected to said first supporting member and adapted to support said second mouthpiece while permitting said second mouthpiece to be moved relatively to said ferrule. 115 120 125

5. In combination a stand adapted to act as a rest for a pillar-type telephone, a flexi- 130

- ble tube, a ferrule shaped so as to fit into the to said mouthpiece, and a stiff, pivoted universal support for said mouthpiece.
5. In combination a telephone transmitter, a mouthpiece for said transmitter, a flexible tube extending from said mouthpiece to said transmitter, a supporting member in the vicinity of said transmitter, and a series of articulated arms joined end to end and 50 extending along said tube from the supporting member to said mouthpiece to hold the mouthpiece in a desired position.
10. In combination a telephone transmitter, a mouthpiece for said transmitter, a flexible tube, a second mouthpiece connected at the other end of said tube, and a second supporting member adapted to support the second mouthpiece and to move relatively to 55 said ferrule.
15. In combination a transmitter, a mouthpiece on said transmitter, a flexible tube, a second mouthpiece on one end of said flexible tube, a ferrule on the other end of said flexible tube shaped to fit into said first mouthpiece, a support for said ferrule, and a support for said transmitter, said supports being so arranged that the ferrule and the first mouthpiece are pressed against each 60 other by gravity.
20. In combination a stand for a pillar-type telephone instrument having a sloping surface on which the instrument sits, a vertically extending projecting member rising from the stand, a ferrule shaped to fit into the mouthpiece of the transmitter of said instrument, supporting means on said member adapted to hold said ferrule at the same height as said transmitter, said ferrule and 25 said sloping surface being inclined to a horizontal plane at the same angle, a flexible tube to which said ferrule is attached at one end, and a mouthpiece attached to the other end of said tube.
25. In combination a telephone transmitter, a mouthpiece for said transmitter, a flexible tube extending from said transmitter to said mouthpiece, and a stiff, universally movable support for said mouthpiece.
30. In combination a telephone transmitter, a mouthpiece for said transmitter, a flexible tube extending from said transmitter to said mouthpiece, and a freely pivoted member for supporting said mouthpiece.
35. In combination a telephone transmitter, a mouthpiece for said transmitter, a flexible tube extending from said transmitter to said mouthpiece, and a stiff, pivoted member 35 for said mouthpiece, and a stiff, pivoted universal support for said mouthpiece.
40. In combination a telephone transmitter, a mouthpiece for said transmitter, a flexible tube extending from said transmitter to said mouthpiece, and a second mouthpiece connected at the other end of said tube, and a second supporting member adapted to support the second mouthpiece and to move relatively to 45 said ferrule.
45. In combination a telephone transmitter, a mouthpiece for said transmitter, a flexible tube extending from said transmitter to said mouthpiece, and a stiff, pivoted member 50 for said mouthpiece, and a stiff, pivoted universal support for said mouthpiece.
50. In combination a telephone transmitter, a mouthpiece for said transmitter, a flexible tube extending from said mouthpiece to said transmitter, a supporting member in the vicinity of said transmitter, and a series of articulated arms joined end to end and 55 extending along said tube from the supporting member to said mouthpiece to hold the mouthpiece in a desired position.
55. In combination a telephone transmitter, a mouthpiece for said transmitter, a flexible tube extending from said mouthpiece to said transmitter, a supporting member in the vicinity of said transmitter, and a series of articulated arms joined end to end in a friction-tight manner and extending along 60 said tube from the supporting member to said mouthpiece to hold the mouthpiece in any desired position.
60. In combination a telephone transmitter, a mouthpiece for said transmitter, a flexible tube extending from said mouthpiece to said transmitter, a supporting member in the vicinity of said transmitter, two series of articulated arms joined end to end in a friction-tight manner and extending along 65 said tube, one series on each side thereof, from the supporting member to said mouthpiece to hold the mouthpiece in a desired position, and straps connecting corresponding joints 70 of said articulated arms to support the flexible tube at intermediate parts.
65. In combination a telephone transmitter, a mouthpiece for said transmitter, a flexible tube extending from said mouthpiece to said transmitter, a supporting member in the vicinity of said transmitter, and a series of articulated arms joined end to end in a friction-tight manner and extending along 75 said tube, one series on each side thereof, from the supporting member to said mouthpiece to hold the mouthpiece in a desired position, and straps connecting corresponding joints of said articulated arms to support the flexible tube at intermediate parts.
70. In combination a telephone transmitter, a mouthpiece for said transmitter, a flexible tube extending from said mouthpiece to said transmitter, a supporting member in the vicinity of said transmitter, and a series of articulated arms joined end to end in a friction-tight manner, one end arm being pivoted to said supporting member and the other end arm being connected to said 80 mouthpiece.
75. In testimony whereof I hereunto affix my signature this 10th day of October, 1927.
80. DOUGLAS STUART SPENS STEUART.
